UNITED STATES PATENT OFFICE

HOWARD F. FORTINBERRY, OF FORT WORTH, TEXAS, ASSIGNOR TO GULF PRODUCTION COMPANY, OF HOUSTON, TEXAS, A CORPORATION OF TEXAS

DUMP AND SEAL-TUBING VALVE

Application filed August 30, 1929. Serial No. 389,512.

This invention relates to devices for automatically draining long strings of tubing of fluids, entrained solids or a mixture thereof. The tool or device may conveniently be designated as a combination dump and seal tubing valve.

One object of the present invention is to provide a tool or device of this character by the use of which practically all waste of oil is eliminated when the well tubing is removed from the well. A further object contemplated is to provide a device that will improve the operation of a pumping oil well. Heretofore there has been a considerable loss of time in operation due to the accumulation of sand or salt or other foreign substances in the working parts of the pumping mechanism, but, by use of the present invention this time element or loss of time is greatly reduced. A still further object is to construct the present device in such fashion that it may be produced at a relatively low cost by reason of the simplicity of its construction. This simplicity of construction also reduces the likelihood of the apparatus getting out of working order.

With these and other objects in view, the invention consists of certain details of construction and combinations and arrangements of parts, all as will hereinafter be more fully described and the novel features thereof particularly pointed out in the appended claims.

In the accompanying drawings,

Figure 1 is a sectional view taken longitudinally of a well casing and illustrating the lower end portion of the pump working barrel which carries the device constituting the present invention,

Fig. 2 is a transverse sectional view on the line 2—2 of Fig. 1,

Fig. 3 is a similar view on line 3—3 of Fig. 1.

As is well understood in the art the pump working barrel 10, the lower portion only of which is illustrated in the present instance, extends down through the well casing 11. Attached to the lower end of barrel 10 is what will be termed a coupling or barrel seat means 12, said coupling having a tapered

center bore 13 which constitutes a valve seat 14 for a valve member 15 whose cross-section corresponds to the bore of coupling 12. For convenience this valve member may be termed a mandrel, and extending through it is a center bore 16, into the upper end of which there is threaded a standing valve nipple 17, on which is secured the usual standing valve 18 for controlling the passage of fluids through said center bore 16. Standing valve 18 may be of any desired type, in the present instance being simply illustrated as a ball 18 within a cage 19.

A portion of the mandrel or valve 15 projects without or below coupling 12, and to the projecting portion of said valve there is attached what will be termed a lower coupling 20, bored to receive the end of said valve 15 as well as a mud anchor 21. In the juxtaposed end surfaces of couplings 12 and 20 are recesses 22 and seated in said recesses is a coil spring 23 surrounding the projecting portion of valve member 15. Normally, the action of spring 23 yielding-ly urges couplings 12 and 20 away from one another for the purpose of maintaining the tapered portion of valve 15 against its seat 14 in coupling 12.

When in use the device is assembled between the working barrel and the mud anchor, as shown, and, when the tubing is run the string is allowed to swing a few inches off the bottom of the well. Under which circumstances the valve 15 will be seated as well by gravity as by the influence of spring 23. As the fluid head builds up in the tubing, the pressure exerted on the top of the mandrel becomes gradually more effective in seating said valve 15, so that a perfectly tight joint is formed. However, if for any reason it should be desired to flush the tubing, said tubing is lowered until the mud anchor comes into contact with the bottom of the well and by further slightly lowering the tubing the coupling 12 will move relatively to coupling 20 so as to unseat valve 15 whereupon foreign substances may drain or escape through the clearance that is then provided between the said valve and its seat 14. After thus flushing the tubing, the lat-

ter is raised until the mud anchor is lifted free of the bottom of the well whereupon the tension of spring 23 together with the weight of the anchor will return the mandrel or valve 15 to its seat 14.

5 What I claim is:

1. In a device of the character described, the combination of a working barrel, a valve seat carried by said barrel, a coupling spaced 10 below said barrel, said coupling and barrel being movable toward and from each other and a valve attached to said coupling and operatively associated with said valve seat, foreign material within said barrel being 15 free to escape at a point between the coupling and valve seat member when said valve is unseated by movement of the barrel and coupling toward each other.

2. In a device of the character described, 20 the combination of a working barrel, a valve seat member carried by said barrel, and a valve movable longitudinally upwardly of the barrel to clear said valve seat, foreign material within said barrel being free to 25 escape through the clearance between said seat and valve when the latter is unseated, and a standing valve nipple carried by said valve.

3. In a device of the character described, 30 the combination of a working barrel, a coupling attached to said barrel and provided with a valve seat, a valve member having a central bore and projecting through said coupling beyond the end of the barrel, said 35 valve member being movable longitudinally upwardly of the barrel away from its seat, and means for yieldingly urging said valve against its seat.

4. In a device of the character described, 40 the combination of a working barrel, a coupling attached thereto and provided with a tapered central bore forming a valve seat, and a tapered valve member adapted to engage said seat and project beyond the lower 45 end of said coupling, said valve member being movable longitudinally upwardly of the barrel to displace it from its seat.

5. In a device of the character described, 50 the combination of a working barrel, a coupling attached thereto and provided with a central bore forming a valve seat, a tapered valve member adapted to engage said seat, said valve being movable longitudinally upwardly of the barrel to displace it from its seat, and means for yieldingly urging the 55 valve against its seat.

6. In a device of the character described, 60 the combination of a working valve, a coupling attached thereto and provided with a tapered central bore constituting a valve seat, a tapered valve adapted to engage said seat and projecting without said coupling, and a second coupling attached to the projecting portion of said tapered valve, said 65

couplings being movable toward each other to unseat said valve.

7. In a device of the character described, the combination of a working valve, a coupling attached thereto and provided with a 70 tapered central bore constituting a valve seat, a tapered valve adapted to engage said seat and projecting without said coupling, and a second coupling attached to the projecting portion of said tapered valve, said 75 couplings being movable toward each other to unseat said valve and a spring interposed between said two couplings yieldingly urging the same away from each other to seat said valve.

8. In a device of the character described, the combination of a working valve, a coupling attached thereto and provided with a tapered central bore constituting a valve seat, a tapered valve adapted to engage said 80 seat and projecting without said coupling, and a second coupling attached to the projecting portion of said tapered valve and movable toward said valve seat to unseat said valve, the opposed surfaces of said couplings 85 having recesses therein, and a spring surrounding the projecting portion of said valve and engaging in the recesses in the couplings.

9. In a device of the character described, the combination of a working barrel, a coupling attached thereto formed with a central bore, a valve member normally closing said bore and projecting without said coupling, a second coupling attached to the projecting portion of said valve member, said 95 valve member being movable longitudinally upwardly of the barrel to open said central bore, and said valve member having a passage therein through which fluid may pass from the coupling attached thereto to said 100 barrel, and a valve for said last mentioned passage.

HOWARD F. FORTINBERRY.
